UNITED STATES PATENT OFFICE.

IRWIN E. COHN, OF NEW YORK, N. Y.

AIR-OPERATED TOY.

Application filed July 21, 1926. Serial No. 124,043.

My invention relates particularly to a toy of the type which affords facilities for making use of air to sound a whistle and to actuate a movable element simultaneously, and it consists in the combinations, constructions and arrangements herein described and claimed.

An object of the invention is the provision of a toy of the character described in which all the movable elements are completely housed and protected from injury and the elements of the toy that are intended to be displayed are visible at all times.

A further object of the invention is the provision in a toy of the character described of a novel and highly efficient means for directing the flow of the exhaust air from the vent of a whistle to effect the operation of an air motor simultaneously with the sounding of the whistle.

A still further object of the invention is the provision of a toy of the character described which has the general appearance of a toy rattle and is adapted to be carried in the hand of a user in substantially the same manner as a toy rattle.

A still further object of the invention is the provision of a toy of the character described which is simple in construction, reliable in use, not likely to get out of order easily, and thoroughly practical commercially.

Other objects and advantages of the invention will be apparent from the following description, considered in conjunction with the accompanying drawings, in which

Figure 1 is a perspective view of the improved toy,

Figure 2 is a longitudinal vertical section through the toy, and

Figure 3 is a fragmentary horizontal section through the toy.

The improved toy includes a housing which comprises a substantially cylindrical body 1 which is shown in the drawing as being disposed vertically. The body 1 is closed at its lower end by a bottom cap 2 and at its upper end by a top cap 3. The top cap 3 can be removed manually but the bottom cap 2 preferably is secured to the body 1 in any suitable known manner and both the caps fit the adjacent ends of the body tightly so as to obviate accidental displacement of the caps from the body.

The space within the body 1 of the housing is divided by a horizontal partition plate 4

into a chamber 5 for an air motor and a chamber 6 for a turntable 7. The chamber 6 for the turntable is shown as being located within the body between the partition plate 4 and the upper or removable cap 3.

The aforesaid air motor may comprise a plurality of vanes 8 which are disposed vertically edgewise and which extend radially from the lower end portion of a vertical spindle 9. The spindle 9 extends centrally of the body 1 through a central opening 10 in the plate 4 and has reduced circular lower and upper end portions 11 and 12, respectively, journaled in bearings 13 and 14 respectively, said bearings being carried by the central portions of the bottom and top caps 2 and 3 respectively. The opening 10 in the partition plate is considerably larger than the portion of the spindle 9 that extends therethrough to permit free rotation of the spindle about its axis. The turntable 7 is shown as being a plate of circular configuration having a central opening through which the spindle 9 extends and in which a portion of the spindle 9 fits tightly so that the turntable 7 will rotate with the spindle and will be disposed horizontally within the chamber 6 above the partition plate 4. A plurality of miniature figures 15 which may be "chicks" as shown in Figures 1 and 2 or other desirable miniature objects or animals, are mounted on the turntable 7 to rotate with the latter and may be arranged in a circular series about the center of the turntable.

The body 1 and the top cap 3 are made of a transparent material, such as celluloid, and the turntable 7, the partition 4 and the bottom cap 2 also may be made of the same material. The elements within the chambers 6 and 5 then will be clearly visible and if desired, the bottom cap 2 may be colored to render it opaque and the body 1, the top cap 3, the turntable 7 and the chicks 15 may be tinted to have some color which will contrast with the color of the bottom cap 2 but will not render the tinted parts of the housing opaque. The vanes 8 may be colored to contrast with the colors of the adjacent walls of the chamber 5 and the miniature objects 15 on the turntable 7 may be colored so that they will be clearly distinguishable from the adjacent walls of the chamber 6 and from the turntable.

A blow tube 16 has the inner end portion thereof secured in an opening 17 in the

portion of the body 1 of the housing that forms a side wall of the chamber 5. The blow tube 16 tapers slightly toward its outer end and has a mouth piece 18 secured there-
 5 to at the outer end of the blow tube. A whistle 19 which may be of well known construction and may comprise two joined together convexo-concave centrally apertured plates as shown in Figure 2, fits in the inner
 10 end portion of the blow tube 16 at a slight distance from the inner extremity of the blow tube. The blow tube 16 may protrude slightly through the opening 17 into the chamber 5 but terminates outwardly of the
 15 circular path in which the outer edges of the vanes 8 will move when the spindle 9 is rotated. A relatively short air deflecting tube 20 of considerably less area in cross section than the cross sectional area of the
 20 inner end portion of the blow tube 16 is joined at its outer end to the whistle 19 in encircling relation to the exhaust aperture in the whistle 19. As shown to advantage in Figure 3, the air deflector tube 20 is sub-
 25 stantially horizontal but is disposed in a direction oblique to the longitudinal axis of the blow tube 16 and extends from the whistle 19 substantially to the inner end of the blow tube 16 so that the exhaust air from
 30 the whistle 19 will be discharged into the chamber 5 at an angle oblique to the longitudinal axis of the blow pipe 16. The blow tube 16 extends radially outward from the body 1 and therefore the blasts of exhaust
 35 air from the whistle 19 will tend to move from the tube 20 horizontally across the chamber 5 at one side of the vertical central line of the chamber 5. The vanes 8 extend from the lower portion of the spindle 9
 40 nearly to the inner side wall of the chamber 5 and therefore the exhaust air from the whistle 19 that enters the chamber 5 through the deflector tube 20 will impinge against a face of each vane 8 as that vane moves in
 45 front of the inner end of the deflector tube and a current of air of relatively slight velocity will cause a relatively rapid rotation of the air motor in the chamber 5. The chamber 5 may be provided with air outlet
 50 ports in the form of a plurality of vertically disposed slits 21 and horizontally disposed slits 22 which are formed in the portion of the body 1 which constitutes the side wall of the chamber 5 and which may be
 55 spaced circumferentially of the body 1.

The blow tube 16 may serve as a handle for use in carrying the device from place to place and in maintaining the device in a desirable position when it is desired to blow
 60 air into the chamber 5 through the blow tube 16, the whistle 19 and the air deflector tube 20. When the device is carried by means of the blow tube 16, the device has the general appearance of a toy rattle. A ring
 65 23 may be attached to the outer end portion

of the blow tube 16 and constitutes a convenient means for suspending the device from a hook not shown, or other fixed support.

From the foregoing description of the 70 various parts of the device, the operation thereof may be readily understood. The user of the device may hold it by means of the blow tube 16 with the mouth piece 18 against his lips, and when he blows air through the 75 blow tube 16 and the whistle 19, the whistle will be sounded and at the same time the air motor will be operated at a relatively high speed and the turntable 7 in the chamber 6 with the miniature figures thereon will 80 be turned about the axis of the spindle 9 in the manner of the turntable of a merry-go-round. The movable elements of the toy are completely housed and thus are protected from injury. Although housed, these 85 movable elements are visible and the conjoint effect of the sounding of the whistle and the motion of the movable elements of the toy will render the toy extremely attractive to children. 90

Obviously, my invention is susceptible of embodiment in forms other than that which is illustrated in the accompanying drawings, and I therefore consider as my own all such modifications and adaptations thereof as 95 fairly fall within the scope of the appended claims.

I claim:—

1. A toy including a housing comprising a substantially cylindrical body formed of transparent material, caps for the opposite ends of said body, a transparent partition intermediate the ends of said body, dividing the body into upper and lower chambers, said partition having a central opening, bearings at the inner sides of the central portions of said caps, a spindle extending through the central opening of the partition and having reduced end portions journaled in said cap bearings, a turntable in the upper chamber and secured to said spindle between said partition and the upper one of said caps, an air motor in the lower chamber and carried by the spindle between the central partition and the lower cap, a blow tube connected at one end with the lower chamber of the cylindrical body for delivering air into said chamber against the air motor, said cylinder having apertures leading into the lower chamber adjacent to said air motor for the escape of the air that has been used to actuate said air motor, and a whistle in the blow tube adjacent to the inner or discharge end thereof. 110

2. A toy including a housing comprising a substantially cylindrical body formed of transparent material, caps for the opposite ends of said body, a transparent partition intermediate the ends of said body, said partition having a central opening, bearings 120

5 at the inner sides of the central portions of said caps, a spindle extending through the central opening of the body and having reduced end portions journaled in said bearings, a turntable secured to said spindle between said partition and one of said caps, an air motor carried by the spindle between the partition and the other cap, and means 10 for delivering a blast of air into said housing against said air motor for causing rotation of said spindle.

15 3. A toy including a housing comprising a substantially cylindrical body formed of transparent material, caps for the opposite ends of said body, a transparent partition intermediate the ends of said body, said partition having a central opening, bearings at the inner sides of the central portions of said caps, a spindle extending through the 20 central opening of the body and having reduced end portions journaled in said bearings, a turntable secured to said spindle between said partition and one of said caps, an air motor carried by the spindle between the partition and the other cap, and means 25 for delivering a blast of air into said housing against said air motor for causing rotation of said spindle, the cap nearest to said turntable, the partition and the turntable all 30 being formed of transparent material.

35 4. A toy including a housing comprising a substantially cylindrical body formed of transparent material, caps for the opposite ends of said body, a transparent partition intermediate the ends of said body, said partition having a central opening, bearings at the inner sides of the central portions of

40 said caps, a spindle extending through the central opening of the body and having reduced end portions journaled in said bearings, a turntable secured to said spindle between said partition and one of said caps, an air motor carried by the spindle between the partition and the other cap, a blow tube 45 connected with said housing for delivering air into said housing against said air motor.

5. A toy comprising a housing having a substantially cylindrical body formed of transparent material, an air motor mounted in said housing body, a combined blow tube 50 and handle connected with said body and extending radially outward from the body, and an obliquely disposed air deflector tube in the discharge end portion of said blow tube for delivering air into said housing 55 body against the air motor at one side of the axis of rotation of the air motor.

6. A toy comprising a housing having a substantially cylindrical body formed of transparent material, an air motor mounted 60 in said housing body, a combined blow tube and handle connected with said body and extending radially outward from the body, and an obliquely disposed air deflector tube in the discharge end portion of said blow 65 tube for delivering air into said housing body against the air motor at one side of the axis of rotation of the air motor, said housing body having a circumferentially spaced series of outlet openings for the escape of the 70 air that has been used to actuate said air motor.
